CLAIM

The ornamental design for a combined phone stand and speaker, as shown and described.

DESCRIPTION

FIG. 1 is a front, right and top perspective view of a combined phone stand and speaker, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an alternate front, right and top perspective view of the combined phone stand and speaker in a position of use; and,

FIG. 10 is another alternate front, right and top perspective view of the combined phone stand and speaker in another position of use.

The broken lines depict portions of the combined phone stand and speaker that form no part of the claimed design.

1 Claim, 10 Drawing Sheets
